UNITED STATES PATENT OFFICE.

JOHN THOMAS, OF MONTREAL, QUEBEC, CANADA.

GAME.

Application filed November 5, 1921. Serial No. 513,096.

To all whom it may concern:

Be it known that I, JOHN THOMAS, a subject of the King of Great Britain, residing at Montreal, Province of Quebec, Canada, have invented certain new and useful Improvements in Games; and I do hereby declare that the following is a full, clear, and exact description of the invention, such as will enable others skilled in the art to which it appertains to make and use the same.

The present invention relates to new and useful improvements in games.

The primary object of the invention is the provision of a game based on the fundamental principles of the ordinary game of poker wherein a plurality of cards are indicated on a board with means provided upon the cards for engaging and holding a ball, a series of which, preferably five in number, are passed over the surfaces of the cards, being caught and held upon the cards to indicate various things corresponding to that of the above mentioned game of poker.

Another object of the invention is the provision of means for projecting the balls upwardly toward the upper end of the board from whence they roll by gravity toward the lower end thereof, being deflected along different lines by means which are attached to the board, causing them to roll over the surfaces of the various card indications until they become caught and held in such position.

A further object of the invention is the provision of an attachment at one side of the board which is removable and which may contain indication marks designating the value of the various points to be used in playing the game.

A still further object of the invention is the provision of means for elevating one end of the board so that the balls will roll across the surface thereof.

Still another object of the invention is the provision of a game such as above referred to which will be comparatively simple and inexpensive to manufacture, reliable and efficient in use, and readily operated.

Another object of the invention is to provide a game which is equally as well adapted for older persons as it is for children.

With the above and other objects in view, the present invention resides in the novel features of construction, formations, combinations and arrangements of parts to be hereinafter more fully described, claimed

and illustrated in the accompanying drawings forming a part of the present application, and in which:

Figure 1 is a top plan view of a game board constructed in accordance with the present invention;

Figure 2 is a transverse sectional view thereof;

Figure 3 is a longitudinal sectional view thereof;

Figure 4 is a longitudinal sectional view taken through the mechanism for projecting the balls;

Figure 5 is a detail sectional view illustrating the means of retaining the side attachment in position;

Figure 6 is a detail perspective view illustrating one means of gripping the balls and holding them in position upon the cards;

Figure 7 is a plan view of a portion of the board surface showing a modified form of the retaining means for the balls including three pins arranged to engage the same; and,

Figure 8 is a detail sectional view showing the pins in side elevation.

Referring now to the accompanying drawings by corresponding characters of reference throughout the several views, the numeral 10 designates in general my improved game board which comprises a bottom 11 which is of substantially rectangular formation, being rounded at its upper end as at 12. A flange 13 extends entirely around the board projecting upwardly from the surface thereof to prevent the displacement of the balls from the board while playing the game. A covering shown at 14 covers the upper surface of the board within the rectangular portion thereof and has marked thereon suitable indications which designate the various cards in a deck of playing cards, such as shown at 15. A suitable retaining device 16 is placed centrally of each of the cards and is designed to engage one of a plurality of balls 17. A channel 18 is provided at one side of the apparatus and within this channel is mounted a spring actuated plunger 19 provided with a suitable handle 20 by means of which the said plunger can be operated to project the balls 17 upwardly toward the curved end 12 of the board allowing them to roll downwardly between the baffle members 21 which deflects the balls in various directions, thus making the game one of purely chance. A suitable pad

22 may be attached to one side of the curved flange 13. This pad 22 is formed of resilient material so as to assist in deflecting the balls at various angles. Other means of engaging 5 and holding the balls upon the various cards may be employed such as the depressions 23 which are preferably arranged alternately between the members 16 or in the form of pins 24 which will likewise retain the balls 10 in the manner described.

A removable attachment of rectangular formation is shown at 25 and is secured in position to one of the side flanges 13 by the dowe's 26, which form a channel 27 in which 15 a scale may be placed, such as shown at 28 indicating the value of the various points which the cards will indicate.

In playing the game the cards count the same as in an ordinary game of poker in the 20 following order:—One pair, two pair, three of a kind or triplets, straight, flush, full house, four of a kind, and straight flush.

The operator first places all or one or more of the balls 17 in the projecting device 25 in advance of the plunger 19 and by drawing the handle 20 rearwardly, the balls are projected toward the curved end 12 of the board and allowed to fall downwardly passing over the various card indications until 30 they are caught and held centrally of the cards. The player then determines what points he has made by seeing whether he has gotten one pair, two pair, three of a kind, etc.

35 One or more trials may be had by the player, that is, after projecting the balls first, he may remove those he does not wish to retain and may project the balance over again over the surface of the board which 40 would correspond to discarding and drawing additional cards in the usual game of poker.

Any suitable elevating device shown at 29

may be attached to the curved end of the board for giving the same the proper elevation for the best operation.

45 From the foregoing description, taken in connection with the accompanying drawings, it will be manifest that a game board is provided which will fulfil all of the necessary requirements of such a device, and it should be understood in this connection that various minor changes in the specific details of construction can be resorted to within the scope of the appended claim, without 50 departing from the spirit or sacrificing any of the advantages of the invention.

55 A certain amount of skill is required in playing the game by pulling the handle 26 in such manner as to direct the balls with 60 different force against the curved portion of the flange 13.

Having thus fully described the invention, what I claim as new and desire to protect by Letters Patent is:—

65 The herein described game board comprising a body portion having a curved upper end, means for elevating one end of the game board, a flange extending around said board, a pad attached to the flange, deflectors secured to the board, a projection mechanism at one side of the board, balls movable over the surface of the board, a covering for said board having indication marks thereon representing the cards of a pack of 70 playing cards, means centrally of each card for engaging the balls and holding 75 them against further movement, an attachment at one side of the board, means for removably holding the attachment in position, said attachment forming a channel, and means within the channel to indicate the number of points and the like for the game.

80 In witness whereof I have hereunto set my hand.

JOHN THOMAS.
